UNITED STATES PATENT OFFICE.

JOHN REICHERT, OF RACINE, WISCONSIN.

RACK.

Application filed September 12, 1928. Serial No. 305,523.

This invention relates to certain improvements in racks; and the nature and objects of the invention will be readily recognized and understood by those skilled in the art 5 in the light of the following explanation and detailed description of the accompanying drawings illustrating what I at present consider to be the preferred embodiments or mechanical expressions of my invention from 10 among various other forms, arrangements, combinations and constructions of which the invention is capable within the spirit and the scope thereof.

The invention is more particularly directed 15 to the garment displaying types of racks utilized for holding and displaying garments and such like articles, in stores, show rooms, and other places of display, although the invention is not limited to such types of racks 20 or to any particular articles to be held and displayed thereby; and a general object of the invention is to provide an arrangement and construction of a rack which is of mechanically simple yet durable construction of 25 relatively small cost to manufacture, and a rack which embodies and combines the essential and highly desirable characteristics of occupying a minimum of space in use, and of holding a maximum number of articles while 30 efficiently displaying such articles.

An important characteristic of the design and construction of rack of the invention resides in its adaptability to manufacture from standard or stock materials with the necessity 35 for a minimum of special parts and fittings, and the resulting substantial reduction in cost of materials, and in the cost to manufacture.

A further object of the invention is to provide a rack and supporting base structure 40 therefor, in which the rack frame is of simple, rigid construction, and in which the design and construction of the supports or bases for the rack are such as to impart rigidity to the frame, and to permit of the application to the 45 rack of considerable lateral, longitudinal, and other forces without upsetting or causing the rack to be displaced from its normal upright position, yet without the necessity of great weight for the frame and supporting base 50 structure.

Another object of the invention is to provide a rack construction capable of being easily and quickly assembled and disassembled without requiring skilled labor or special tools, which when disassembled can be 55

readily and compactly packaged for shipment, and which when assembled for use presents an attractive and pleasing appearance but with a minimum of obstruction to or detraction from a view of the articles on 60 display by the rack.

With the foregoing general objects and results in view, as well as certain others which will be apparent from the following explanation, the invention consists in certain novel 65 features in construction and in combinations and arrangements of parts, as will be more fully and particularly referred to herein-after.

Referring to the accompanying drawings, 70 in which similar reference characters refer to corresponding parts throughout the several figures thereof:

Fig. 1, is a view in side elevation of a garment display rack of the invention. 75

Fig. 2, is a view of the rack of Fig. 1 in end elevation.

Fig. 3, is a sectional view taken on the line 3—3 of Fig. 1 showing the frame vertical standards or side uprights in transverse section, and the supporting base structure in top plan. 80

Fig. 4, is an enlarged detail view in side elevation of the upper end of a frame upright showing the cross braces and tie rods with the 85 clamps therefor securing the same to the frame upright.

Fig. 5, is a detail view in elevation of the outer tie rod clamp.

Fig. 6, is a detail view in elevation of the 90 inner tie rod clamp and brace rod receiving support.

Fig. 7, is a vertical section through the upper end of the frame showing the construction and mounting of the tie rods and cross 95 brace bars between the frame uprights.

Fig. 8, is a transverse horizontal section taken on the line 8—8, of Fig. 7.

Fig. 9, is a vertical longitudinal section taken on the line 9—9, of Fig. 3, and showing 100 the arched channel base or foot member with the upright receiving bar in position held therein by the channel cross bars of the base structure.

Fig. 10, is a perspective view of the upright 105 receiving member of the base structure.

Fig. 11, is a vertical section taken on the line 11—11, of Fig. 9.

Fig. 12, is a view in side elevation of a 110 modified form of rack of the invention.

Fig. 13, is a detail perspective view showing the modified construction of the supporting base structure of the rack of Fig. 12.

Fig. 14, is a perspective view of the upright 5 receiving member of the base structure of Fig. 13.

Fig. 15, is a detail vertical section through the upper end of a frame upright of the rack of Fig. 12.

Fig. 16, is a vertical section taken on the line 16—16, of Fig. 12.

Fig. 17, is a vertical section taken on the line 17—17, of Fig. 13.

One possible design and construction of 15 rack of the garment displaying type for store, showroom, and the like uses, and embodying the several features of the invention, is presented in Figs. 1 and 2 of the accompanying drawings by way of example and 20 not of limitation. Such example of rack includes the supporting base structure comprising the spaced, transversely disposed and parallel bases or supporting feet forming bars or members 10, connected by and secured to the spaced longitudinal bracing 25 cross bars 11; and the rack frame structure comprising the vertical side members or uprights 20 secured at their lower ends to and supported on the base members 10, and the 30 horizontally disposed cross bars or brace members 21 secured to and between the upper ends of uprights 20, to form supporting members from and on which articles to be 35 displayed may be supported, as will be later explained.

The base members 10, referring now to 40 Figs. 2, 3, and 9 in particular, are constructed of channel iron of preferably standard or readily obtainable stock materials and sizes, 45 although the invention is not so limited, and are each formed centrally arched to provide the intermediate elevation 10^a and the spaced opposite end and depending supporting feet 10^b. The channels of the base members 10 are disposed on and opening upwardly from 50 the upper sides of the members, and longitudinally along the elevations 10^a, where they form seats for receiving and interlocking with certain hereinafter described structure.

55 A frame upright supporting and base member interlocking and clamping structure or member 30, in the example hereof formed of a single integral casting although not limited to such formation, is provided for mounting on and clamping to each base member 10. Each member 30 in the present instance, 60 comprises a bar or elongated block 31, referring to Figs. 9, 10, and 11, formed to fit and be received in the open channel on the upper side of base elevation 10^a and interlock therewith against lateral movement therein, the bar 31 in cross section conforming to the internal cross section of the base member channel (see Fig. 11). This bar or block 31 is formed on 65 its upper side with an intermediate boss 32

having an internally threaded axial bore, which in the example hereof extends downwardly through bar 31 (see Fig. 9), although not so limited, for receiving and in which the lower end of a frame upright 20 is mounted 70 and secured. Adjacent the opposite ends of the bar or block 31, transversely disposed parallel ribs 33 are formed across the upper side thereof and are extended laterally a distance outwardly beyond one side of the bar 75 31, with the outer ends of these spaced parallel ribs connected and braced by a cross bar 34 extending therebetween across the lower or under sides of the ribs 33, as will be clear by reference to Figs. 10 and 11 of the drawings. 80

The depth of the channel of each elevation 10^a of the members 10, is greater than the thickness of the bars 31 of members 30, so that the ribs 33 are slightly cut away on their under sides at 33^a between bar 31 and the 85 extended rib brace bar 34, on each member 30 to permit the ribs to fit over and across the upper edge of the member 10 channel. Similarly, the unextended ends of ribs 33, overhang the adjacent channel edge slightly and 90 form the under shoulders 33^b fitting down on the channel side wall edge. Each rib 33 is also transversely channeled or cut away above the bar 31 and above the bracing cross bar 34 adjacent the rib ends, so that a series of spaced 95 seats 35 are formed presenting upper bearing faces. Vertical bores 36 are formed downwardly through each rib 33 and the bar 31 therebelow to receive clamping bolts by which the structure or member 30 is secured in position on a base member 10. The foregoing 100 details of construction of the illustrated form of the members 30, are clearly shown in Figs. 10 and 11, of the drawings.

A member 30 is mounted on each base member 10, with the bar or block 31 thereof seated and received in the channel of the elevation 10^a, and the ribs 33 disposed extending inwardly toward the opposite base member 10, and alined with the inwardly extending ribs 33 of member 30 mounted on such opposite base member. The bracing cross bars 11, are formed from channel iron, preferably of standard or readily obtainable stock sizes and material, but of course not limited to such 115 materials or sizes, and are each mounted with the channel side downward, on and extending between a pair of the opposite alined ribs 33 of members 30, with the opposite ends thereof fitting on and over ribs 33, which ribs are received in the cross bar channel with the 120 seats 35 of the ribs 33 providing the supports on which the cross bar 11 seats and rests. The base structure so formed is secured in assembled position by bolts 37 (see Figs. 9 and 10) extended downwardly through the ends 125 of bracing cross bars 11, bores 36 in the ribs 33 and bars 31 of members 30, and the base members 10.

The supporting feet forming base members 130

10 are maintained in spaced relation by the bracing cross bars 11, while the structure is maintained rigid and braced against distortion and twisting by the ribs 33 seated in the 5 channels of bars 11, and the bars 31 of members 30 seated in the channels of the base members 10. The members 30 interlock, and through bolts 37 bind, the base members 10 and cross bars 11 together in position, with 10 the bars 31 preventing lateral or twisting movements of base members 10, and the ribs 33 disposed transversely thereto, preventing lateral or twisting movements of bars 11. The supporting base structure so formed is 15 absolutely rigid and firm under all conditions encountered in use, yet with a minimum of space occupying a heavy, expensive, and cumbersome structure.

The frame structure of the rack is carried 20 and supported on the hereinbefore described base structure, and in the example hereof, includes the vertical standards or uprights 20, which are preferably although not necessarily formed of metal tubing, of standard or 25 stock material and sizes, such for example as the readily obtainable and relatively inexpensive standard gas piping. The uprights 20 are externally threaded at their lower ends and mounted and secured in the internally 30 threaded bores of the bosses 32, respectively, of the bars 31 (see Fig. 9 in particular) and extend upwardly from opposite ends of the base structure in substantially parallel relation to provide the opposite sides of the frame 35 structure as will be clear by reference to Fig. 1 of the drawings.

The upper ends of the frame uprights 20, 40 are connected together and braced by vertically spaced cross bars 21 and tie rods 22, referring now to Figs. 7 and 8 of the drawings, the cross bars 21 extending between the inner sides of uprights 20, and the tie rods extending through the cross bars 21, respectively, and uprights 20 to secure the cross bars 21 and 45 uprights 20 together. At each end of the cross bars 21 is a clamping plate 23, which at one side is formed with a socket 24 having the bar end receiving shoulders 25 at the inner end thereof, (see Figs. 6 and 8 in particular) while at its opposite side the clamping 50 plate is formed curved to fit over and against the adjacent frame upright 20, each clamping plate having a central opening therethrough axially of the socket 24. Each cross bar 21 is mounted between uprights 20 with the clamping plates 23 between the ends thereof and uprights 20. A tie rod 22 is extended through each cross bar 21 and its 55 end clamping plates 23, and transversely through the uprights 20, with the curved clamping plates 26 disposed over the tie rod ends against the uprights 20. The tie rods 22 are in the present example headed at one end and secured in position binding and securing the uprights 20 clamped against cross

bars 21, between clamping plates 23 and 26, by means of a nut 27 threaded on the opposite end against the adjacent clamping plate 26.

The frame structure is completed and braced by the vertically spaced cross bars 70 21 and tie rods 22 between and connecting the upper ends thereof, while the lower cross bar 21 forms a member for and from which the garment supporting hangers 75 can be removably mounted for displaying garments. If desired the lower cross bar 21 and tie rod 22 can be removed and remounted at a lower position as indicated by dotted lines in Fig. 1, to permit of displaying 80 two rows of short garments on the rack. The uprights are preferably bored transversely at such lower or intermediate position to permit of the lower cross bar and tie rod being mounted at such location when desired. Hook members, such as 28 having 85 clamps 29 for attaching the same, are provided for mounting on the frame uprights, and a price or legend card holder 28' can be clamped onto the upper cross bar 21, as shown in Fig. 1.

The rack hereinbefore described, is designed for resting upon the floor and is of sufficient height to display, for example dresses or other full length garments, but in Figs. 12 to 17, inclusive, a modified form of 90 rack is disclosed of smaller size for counter or table use in displaying, for example, short length or small garments. In this form of the rack the base structure remains substantially the same and embodies the base members 10 with bracing cross members 11, but of 95 smaller size than in the form of rack of Fig. 1. Due to the smaller size and weight, with the lessened strength requirements, the interlocking and clamping members 30 of the base structure have the ribs 33' thereof unconnected at their outer ends by any bracing cross bar, but otherwise remain substantially the same as members 30 hereinbefore described.

In this counter form of rack, the frame 100 structure embodies the opposite side vertical members or uprights 20', mounted in a manner hereinbefore described with respect to uprights 20, namely, threaded at their lower ends in the bosses 32 of the bars 31 in base 105 members 10. The upper ends of uprights 20' are braced and connected in the rack of the form of Fig. 12, by a suitable wire or rod cross bar 40 extended between and fitted or 110 extended into the open upper ends of these 115 uprights. This is accomplished in the present instance by forming, as by bending, the opposite ends of wire or cross bar 40 into the vertically disposed hooks 41, having the 120 depending ends 42 (see Figs. 15 and 16) removably fitting into the upper ends of uprights 20'.

Fittings 43 having vertical sockets formed 125 therein for receiving the upper ends of uprights 20', are provided for mounting on and 130

- over the ends of the frame uprights, and each fitting 43 has an axial bore through the upper end thereof opening into the upright receiving socket to receive an end 42 of rod 40, with this rod in mounted position. Each upright end fitting 43 is formed with a laterally extending hook 44, and a vertically disposed socket member 45 for removably receiving a card or the like holder 46, as shown in Fig. 12.
10. Preferably, each upright end fitting 43 is removably secured in position on the upper end of a frame upright 20' by means of a set screw or the like 47, as clearly shown in Fig. 16 of the drawings.
15. The supporting base structure with the spaced base members 10 clamped to and interlocked with the spaced cross bracing bars 11, through the interposed locking member or structure 30, is such that distortion of 20 twisting of such base structure is eliminated, and a very rigid, durable base for the rack results. Further, the construction and arrangement reduces the effect of lateral or upsetting forces applied to a side of the rack, 25 by evenly distributing and neutralizing such forces. The mounting and construction of the frame structure results in a rack of extreme rigidity and strength in use, while retaining light weight with durability, and 30 the requirement for minimum space, and all with a structure which can be relatively cheaply manufactured.

It is also evident that various changes, 35 variations, modifications, and substitutions might be resorted to without departing from the spirit and scope of my invention, and I do not wish to limit myself to the exact and specific disclosures hereof.

What I claim, is:

40. 1. In a rack, a supporting base comprising spaced feet forming channel bars, spaced channel bar cross bracing members disposed transversely of and extending between and secured at their opposite ends to said feet forming bars, and a member interposed between the ends of said cross members and the feet members to which attached, engaging and fitting in the channels of said cross members and feet members, respectively to rigidly lock said members against relative movement.
45. 2. In a rack, spaced opposite end and transversely disposed feet forming members each having a longitudinal groove in its upper side, spaced, substantially parallel cross bars extending between and connected at their opposite ends to said feet members respectively, said cross bars longitudinally grooved on their under sides at the ends 50 thereof, and a locking member interposed between each foot member and the ends of said cross bars and engaged in the grooves of the cross bars and the feet members to rigidly lock said members against relative 55 lateral movements.

3. In a rack, spaced transversely disposed foot members, spaced substantially parallel cross bars extending between and secured at their opposite ends to said foot members, respectively, and a member interposed between each foot member and the ends of the cross bars secured thereto, engaging with the cross bars and the foot member to lock the same against lateral movements, respectively. 70

4. In a supporting base structure, in combination, a foot member having a longitudinal groove in its upper side, a bracing cross member secured at one end to said foot member disposed transversely with respect thereto, said cross member having a longitudinal groove in its under side, and a locking member interposed between said foot member and cross member, said locking member fitting in the groove of said foot member and provided with a transverse upwardly extending projection fitting in the groove of said cross member, said locking member securing the cross member and foot member against relative lateral movement. 75

5. In a rack, spaced, transversely disposed foot forming channel bars having the channels on the upper side thereof, spaced, substantially parallel bracing channel bars having the channels on the under side thereof, extending between and secured at their opposite ends on said foot forming bars, respectively, and a locking member interposed between each foot bar and the ends of the cross bars thereon, said locking member comprising a bar fitted in the channel of the 90 foot bar, and upwardly and laterally extended ribs fitting into the channels of said cross bars, respectively, to rigidly retain the foot bars and the cross bars against lateral movement. 95

6. In a rack, spaced, transversely disposed foot forming channel bars having the channels on the upper sides thereof, spaced substantially parallel bracing channel bars having the channels on the lower sides thereof, 100 said bracing bars extending between said foot members with their opposite ends across the upper sides of said foot forming bars, a locking member interposed between each foot forming member and the ends of the bracing 105 bars, embodying a bar fitting into the channel of the foot bar, and upwardly and laterally extended projections thereon fitting into the lower side channels, respectively, of the bracing bars thereabove, and clamping 110 bolts extending downwardly through the bracing bars, locking member, and foot forming member, to secure the same in position with the locking member maintaining the bracing bars and foot members against relative movement. 115

7. In a rack, spaced foot forming members disposed transversely of the rack, spaced cross bars extending between and secured at their opposite ends to said foot forming mem- 120 125 130

bers, a locking member interposed between and engaging each foot member and the ends of the cross bars secured thereon to prevent relative movement of the foot forming members and cross bars, and rack frame uprights mounted on and carried by said locking members, respectively.

8. In a rack, spaced transversely disposed foot forming channel bars having the channels on the upper sides thereof, spaced, substantially parallel bracing channel bars having the channels on the under sides thereof, said bracing bars extending between and secured at their opposite ends on the upper sides of said foot forming bars, respectively, a locking member interposed between each foot bar and the ends of the bracing bars thereon, said members each embodying a bar fitting in the channel of the foot bar, and upwardly and laterally extended spaced projections fitting into the under side channels of said bracing bars, respectively, and rack frame uprights secured on and carried by the bars of said locking members between the ends of said bracing bars.

9. In a supporting base structure, a foot

member having a longitudinal groove on one side thereof, a bracing member secured to said foot member and extending across the grooved side of the foot member, and a member disposed transversely of and extending from the bracing member fixed with respect thereto, and seated and engaged in the foot member groove to retain and brace the foot member and bracing member against relative lateral movements.

10. In a supporting base structure, a foot member, a bracing member having a longitudinal groove on one side thereof, said bracing member secured to said foot member with the bracing member groove disposed transversely of the foot member, and a member disposed transversely of and extending from the foot member, fixed with respect thereto and seated and engaged in the bracing member groove to retain and brace the foot member and bracing member against relative lateral movements.

Signed at Racine, county of Racine, State of Wisconsin, this 10th day of September, 1928.

JOHN REICHERT.
